UNITED STATES PATENT OFFICE.

WILLIAM H. MYERS, OF SPRINGFIELD, OHIO, ASSIGNOR OF ONE-HALF TO
JOHN F. BARKLEY, OF SAME PLACE.

HYDROCARBON-OIL BURNER.

SPECIFICATION forming part of Letters Patent No. 405,901, dated June 25, 1889.

Application filed April 7, 1888. Serial No. 269,997. (No model.)

To all whom it may concern:

Be it known that I, WILLIAM H. MYERS, a citizen of the United States, residing at Springfield, in the county of Clark and State of Ohio, have invented certain new and useful Improvements in Hydrocarbon-Oil Burners, of which the following is a specification, reference being had therein to the accompanying drawings.

10 This invention relates to certain new and useful improvements in hydrocarbon - oil burners.

The objects of the invention are to spread the oil in a thin sheet or film within a retort for the purpose of readily and quickly vaporizing it, and to automatically regulate the supply of oil to the retort by an automatic valve having also the function of cutting off any back action due to a pressure in the retort in excess of the pressure of the oil supply to the retort.

Another object of my invention is to produce a combined illuminating and heating oil-burner, and so arranged as to perform one 25 of these functions without performing the other.

In the accompanying drawings, forming a part of this specification, and on which like reference-letters indicate corresponding parts,

30 Figure 1 represents an elevation of an ordinary heating-stove with portions thereof removed for convenience of illustration and of my improved burner mounted thereon; Fig. 2, a vertical sectional view of the burner proper; Fig. 3, a detail sectional view of portions thereof on a larger scale; Fig. 4, a horizontal sectional view showing the interior in plan; and Fig. 5, a sectional view of the burner, showing the deflector in plan.

40 The letter A designates a heating-stove of any of the usual or any approved types, upon the grate-bars D of which I mount my improved burner. This consists of a metallic (preferably cast-iron) retort C, the preferred 45 shape of which is similar to a sphere, and the lower portion of which is tubular, as seen at D in Fig. 2. In the tubular portion I fit any convenient number—say three or six—of burner-tips E, preferably made of brass and provided 50 with a small orifice through which the vapor

or gas (as the case may be) generated from the oil issues for ignition. In the lower end of the tubular portion D is fitted, preferably by means of screw-threads, an oil-tube F, which extends through the tubular portion 55 and terminates within the sphere-like portion or retort proper, and to which at a suitable altitude within the said retort proper is connected a diaphragm G. The preferred form of diaphragm is convex on the upper 60 side, while at the periphery it is serrated or otherwise made irregular with respect to the adjacent wall of the retort for the purpose of affording passages to establish communication between the upper and lower 65 compartments of the retort, of which the diaphragm constitutes the dividing-wall. The function of the diaphragm is to receive the oil which flows gradually up through the tube F and spread the same in a thin sheet or film, 70 whereby it is more easily and quickly vaporized. Whatever oil drops down from the diaphragm is subsequently vaporized, and the vapor, finding an escape through the burner-tips E issues therefrom and is ignited, as 75 above intimated. An oil-supply pipe H communicates with the oil-tube at one end and at the other with a suitable tank or oil-supply.

80 The letter I designates a deflector, which is circular and cup-shaped, so as to extend upward opposite the burner-tips and deflect the flames against the retort, so as to heat the same more intensely. At intervals the deflector is provided with openings J, which, 85 when placed opposite the burner-tips, as suggested in Fig. 5, allow the flames to proceed more directly toward the walls of the stove. From this it will be understood that the deflector can be adjusted in a rotary direction 90 to subserve this purpose. It is preferably mounted as seen in Fig. 2—that is, it is screwed upon the oil-tube F and held between the tubular portion D and the oil-supply pipe H. Within the oil-tube, whose upper end is 95 fashioned to form a seat K, is loosely placed a valve-stem L, having a flaring head M. The pressure of the oil on its way to the retort raises this valve-stem sufficient to admit the required quantity to the diaphragm, whence 100

it spreads and vaporizes in the manner already communicated. Should the pressure in the retort become in excess of that of oil, the valve-stem reacts and prevents any communication between the retort and the oil-supply—a valuable feature looking to the safety of the device and entirely automatic. The cut-off of the supply-pipe, as seen in Fig. 1, is regulated to admit to the oil-tube F only sufficient oil to raise the valve L and merely admit the oil to the diaphragm, and hence any pressure in the retort exceeding that of the oil, occasioned by a too rapid expansion of the vapor, will overcome the suspended valve and depress it. This is the operation that takes place in the practical use of this device, as I have ascertained by experience with it.

The letter O designates a vapor or gas pipe rising from the retort and extending above the stove, where it is supplied with a burner pillar and tip P of the kind usually used upon gas-chandeliers. A part of the vapor or gas generated in the retort can thus be utilized for illuminating purposes. The pipe O may have several branches, or may extend in any required direction other than up through the stove, though it is preferred to conduct it more or less upward through the stove for the purpose of subjecting it to the superheating action of the flames arising from the fuel discharged from the tips E. Thus superheated the gas or vapor is found to produce a clear white flame, excellently adapted to illuminating purposes. I contemplate using the burner proper, however, without the illuminating attachment in some instances, though I have subjected both to actual usage and derived the above results therefrom. I have also ascertained that after the retort has become thoroughly heated the flames become clearer and more nearly white, even though the superheating action above referred to is not had.

Referring now to the operation of my improved burner, I desire to say that the usual draft-openings in the lower part of the stove

containing the burner are opened, and the oil turned on until a sufficient quantity has collected in the cylindrical portion D to spirt 50 out of the burner-orifices. Here it is ignited, and the resulting heat in a few minutes vaporizes this collected quantity of oil, and as the retort becomes heated the small quantity of inflowing oil is gradually vaporized and 55 then the amount of oil increased to agree with the amount of heat required. After the parts become thoroughly heated, the amount of oil can be determined and the same heat maintained for any length of time. Such has been 60 the case in the practical operation of this device, it having been tested and used for domestic purposes.

Having thus fully described my invention, what I claim as new, and desire to secure by 65 Letters Patent, is—

1. In an oil-burner, the combination, with a retort having a cylindrical extension, of burners in the vertical walls of the extension, an oil-supply tube leading into the retort, and a deflector below the extension having openings or spaces formed in its outer edge, substantially as described.

2. In an oil-burner, the combination, with a retort having a cylindrical extension and a 75 valved oil-supply tube leading into the retort, of a curved diaphragm or spreader having serrated edges located within the retort, substantially as described.

3. In an oil-burner, the combination, with a retort having a cylindrical extension from its under side and a burner at its upper side and burners in the walls of the extension, of an oil-tube leading into the retort through the extension, a diaphragm or spreader secured 85 on the end of the tube within the retort, and a deflector below the extension, substantially as described.

In testimony whereof I affix my signature in presence of two witnesses.

WILLIAM H. MYERS.
